UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

DEEP-WELL PUMP.

1,230,554.

Specification of Letters Patent. Patented June 19, 1917.

Application filed May 1, 1915. Serial No. 25,178.

To all whom it may concern:

Be it known that I, LARS W. BODINSON, a citizen of the United States, residing at Aurora, in the county of Kane and State of Illinois, have invented certain new and useful Improvements in Deep-Well Pumps, of which the following is a specification, reference being had to the accompanying drawings.

10 This invention relates to deep well pumps of the reciprocatory type and it has for its principal object the provision of a new and improved form and arrangement of parts by which a very great amount of water 15 can be forced upward through a comparatively small bore. For the accomplishment of this purpose, I have provided a stationary cylinder and three movable cylinders all in alinement with each other, three plungers 20 movable with said three movable cylinders, and three other plungers working in said movable cylinders, said three movable cylinders and their connected plungers being adapted to be reciprocated in unison by one 25 pump rod and the plungers in the movable cylinders being adapted to be reciprocated in unison by another pump rod. It is one 30 of the objects of my invention to improve the form and operation of pumps of this type in sundry details hereinafter pointed out. The preferred means by which I have 35 accomplished my several objects are illustrated in the accompanying drawings and are hereinafter specifically described. That 40 which I believe to be new and desire to cover by this application is set forth in the claims.

In the drawings:—

Figure 1 is a central vertical section through the upper part of the pumping apparatus located in the bottom of the well;

Fig. 2 is a central vertical section through the lower part of the pumping apparatus in the bottom of the well, being a downward continuation of the parts shown in Fig. 1;

Fig. 2^a is a diagrammatic view illustrating a form of driving means adapted for reciprocating the pump rods in opposite directions; and

Figs. 3, to 11, inclusive, are horizontal 50 cross-sections on the correspondingly-numbered section lines of Figs. 1 and 2.

Referring to the drawings in which cor-

responding parts are indicated by the same reference characters,—

20 indicates a well tube, to the lower end 55 of which, through the medium of a screw-threaded coupling device 21, is secured a stationary cylinder 22 preferably made of brass. A plunger 23 is adapted to be reciprocated, by the means hereinafter described, 60 in the cylinder 22. A second cylinder 24 is connected at its upper end to the plunger 23, and a third cylinder 25 is connected to the lower end of the cylinder 24 by means of a coupling member 26 which serves as a closure member for the upper end of the said cylinder 25 which is provided with an annular inlet opening for the cylinder 24. A fourth cylinder 27, preferably made of brass, is connected to the lower end of the 70 cylinder 25 by means of a member 28 which serves as a coupling, as above described, and also as a plunger as will appear hereinafter, serving also to provide an inlet port for both of the cylinders 25 and 27. The lower 75 end of the cylinder 27 is provided with a plunger 29 movable therewith.

In the cylinders 24, 25 and 27 are three 80 plungers 30, 31 and 32, respectively, suitably connected together, as hereinafter described, and adapted to be operated in unison in the said three cylinders.

Secured to the lower end of the stationary cylinder 22 and extending downward about the three movable cylinders serving 85 as a suction pipe for the several plungers, is a pipe or tube 33, having connected to its lower end below the lowermost movable cylinder a valve-cage 34 provided with an upwardly-opening valve 35 of any suitable 90 type. A lower suction pipe 36 extends downward from the valve 35 to the limit of the suction power of the pumping apparatus, whereby the pump is prevented from sucking air as the level of the water in the well is 95 lowered by continued pumping.

The means for reciprocating the plungers 30, 31 and 32 in unison comprises a pump rod 37, having connected to its lower end a tubular pump rod section 38, such 100 connection being effected by the use of a coupling 39 which leaves the upper end of the tubular pump rod section open. The plunger 30 is connected to the pump rod

section 38 by means of a coupling sleeve 38^a which serves as a stop for limiting the upward movement of the upwardly-opening valve 40 of the said plunger. The plunger 30 is provided with packing 41 of any suitable type bearing upon the inner face of the cylinder 24. Connected to the plunger 30 and extending downward therefrom is another tubular pump rod section 42 which 5 extends through the coupling member 26, having packing 43 arranged in such coupling member thereabout. A coupling 44 serves to connect the lower end of the tubular pump rod section 42 with the plunger 31, said coupling serving as a stop for limiting the upward movement of the upwardly-opening valve 45 of the said plunger 31. The plunger 31 is provided with packing 46 of any suitable type bearing 10 upon the inner face of the cylinder 25. Connected to the plunger 31 and extending downward therefrom is another tubular pump rod section 47, to the lower end of which the plunger 32 is connected. The 15 plunger 32 is hollow, communicating with the lower end of the pump rod section 47, an upwardly-opening valve 48 being provided for preventing the escape of water downward from the said pump rod section. 20 Packing 49 is secured about the plunger 32 bearing on the inner face of the cylinder 27.

The means for reciprocating the movable cylinders and the plungers carried thereby comprises a tubular pump rod 50, to the lower 25 end of which there is connected a large tubular pump rod section 51 which surrounds the coupling member 39. The connection between the pump rod 50 and the tubular pump rod section 51 is effected through the 30 use of a coupling 52 which provides a large annular opening from the said pump rod section into the well tube 20. The plunger 23 is connected to the pump rod section 51 by means of a sleeve 53, suitable packing 35 54 being provided between said sleeve and the stationary cylinder 22. The plunger 23 is also provided with suitable packing 55 about the tubular pump rod section 38, and is provided with an upwardly-opening 40 valve 56 of any suitable type. The plunger 28 is provided with an upwardly-opening valve 57 and with suitable packing 58 about the tubular pump rod section 47. The plunger 29 is provided with an upwardly-opening 45 valve 59 of any suitable type.

With the plunger rods 37 and 50 being reciprocated by any suitable means in opposite directions, the operation will be as follows:—Upon the upward movement of the 50 pump rod 37 and the downward movement of the pump rod 50, the lower end of the cylinder 27 will be filled with water through the valve 59, while the water in the upper end of the said cylinder 27 will be forced

through the valve 57 of the plunger 28 into the cylinder 25 below the plunger 31. At the same time the water in the cylinder 25 above the plunger 31 will be forced through the coupling 44 upward through the tubular pump rod sections 42 and 38 and delivered into the tubular pump rod section 51 above the plunger 23, constituting two quantities of water delivered above the plunger 23, one quantity displaced by a full downward stroke of the closure member 26 70 and the other displaced by a full upward stroke of the plunger 31. At the same time the cylinder 24 is being filled with water below the plunger 30 through the coupling member 26, while the water in the cylinder 24 above the plunger 30 is being forced upward through the valve 56 of the plunger 23, constituting two additional quantities of water so delivered above the plunger 23, one of such additional quantities of water being 80 displaced by a full downward stroke of the plunger 23 and the other by a full upward stroke of the plunger 30. Thus four substantially equal quantities of water are delivered above the plunger 23 while that 85 plunger is moving downward a full stroke, leaving a net gain of three quantities actually raised.

Upon the downward movement of the pump rod 37 and the upward movement of the pump rod 50, the water in the lower end of the cylinder 27 will be forced upward through the valve 48 of the plunger 32 and thence upward through the pump rod sections 47, 42 and 38 into the pump rod 100 section 51 above the plunger 23, constituting two quantities of water delivered above the plunger 23, one quantity displaced by a full downward stroke of the plunger 32 and the other displaced by a full upward 105 stroke of the closure member 29. At the same time the upper end of the cylinder 27 is filled above the plunger 32 through the combination coupling member and plunger 28. At the same time the water in the cylinder 25 below the plunger 31 passes upward through the valve 45 of the plunger 31 but still remains in the upper end of the cylinder 25, the valve 57 serving to prevent the water from escaping from the tube 42 into the already filled cylinder 25. At the same time the water in the cylinder 24 below the plunger 30 passes upward through the valve 40 of the plunger 30 but still remains in the upper end of the cylinder 24. At the same 110 time the water in the stationary cylinder 22 above the plunger 23 is forced upward by a full upward stroke of the said plunger 23. Thus it will be seen that upon the downward movement of the pump rod 37 and the upward movement of the pump rod 50, there have been two quantities of water delivered above the plunger 23 while that 115 120 125

plunger was by a full upward stroke raising another quantity, making a total of three quantities actually raised.

- 5 The form of means shown for reciprocating the pump rods 37 and 50 in opposite directions comprises cross-heads 60—61 connected to said pump rods respectively, said cross-heads being slideable vertically in suitable slots 62—63 provided by a frame 64.
- 10 The cross-heads 60 and 61 are connected by means of links 65 with suitable offset portions of a crank-shaft 66 which is adapted to be driven from any suitable source of power by means of a drive-wheel 67.
- 15 It is thus seen that by my improved arrangement of plungers and cylinders, I am enabled by the use of two pump rods to raise six quantities of water at each complete cycle of operation of the pump rods,
- 20 each of such quantities of water being equal to the amount raised by an operative stroke of a single plunger. It will be seen that the amount of water raised upon the down stroke of one pump rod is substantially the
- 25 same as that raised upon the down stroke of the other pump rod. I have thus provided pumping means of great efficiency, both as to the amount of water capable of being raised and as to the balanced condition which exists throughout the operation of the pump.

What I claim as my invention and desire to secure by Letters Patent, is:

1. In a pump, the combination of two aligned cylinders, means for reciprocating said cylinders in unison, plungers operated in said cylinders, and a pipe extending through the upper plunger into the lower cylinder through which the water is adapted to be forced by the reciprocation of said cylinders from the lower cylinder into position above the uppermost plunger.

2. In a pump, the combination of two aligned cylinders, means for reciprocating said two cylinders in unison, plungers in said cylinders, and a tubular pump rod connected with said plungers for reciprocating them in unison in said cylinders, the reciprocation of said cylinders and said plungers in opposite directions serving to force the water in the lower cylinder upward through the tubular pump rod into position above the uppermost plunger.

3. In a pump, the combination of two aligned cylinders, means for reciprocating said two cylinders in unison, two plungers in said cylinders respectively having upwardly-opening valves therethrough, a tubular pump rod connected with said two plungers for reciprocating them in unison, each of said cylinders being adapted upon its downward stroke to take in water at its lower end, and means for preventing the escape of the water at the lower ends of said

cylinders upon their upward stroke, the reciprocation of said cylinders and said plungers in opposite direction serving to force the water in the lower cylinder upward through the tubular pump rod into position above the uppermost plunger.

4. In a pump, the combination of a well tube, an upwardly-opening valve therein, a cylinder mounted in said well tube and held out of contact with the walls thereof, an upwardly-opening valve in the lower end of said cylinder, means for reciprocating said cylinder, a plunger in said cylinder, a tubular pump rod connected with said plunger for reciprocating the plunger, and an upwardly-opening valve in said pump rod through which the water in the cylinder below the plunger is adapted to pass upward.

5. In a pump, the combination of a movable cylinder, a tubular pump rod extending down through said cylinder, an upwardly-opening valve about said pump rod at the lower end of said cylinder through which valve water is adapted to enter said cylinder, means for reciprocating said cylinder, a plunger in said cylinder connected with said tubular pump rod, and an upwardly-opening valve through said plunger.

6. In a pump, the combination of a movable cylinder, a tubular pump rod extending down through said cylinder, an upwardly-opening valve about said pump rod at the lower end of said cylinder through which valve water is adapted to enter said cylinder, means for reciprocating said cylinder, a plunger in said cylinder connected with said tubular pump rod, means for closing the upper end of said cylinder about said tubular pump rod, and an upwardly-opening valve through said plunger, said tubular pump rod being provided with a port opening into the cylinder above the plunger.

7. In a pump, the combination of a movable cylinder, a tubular pump rod extending down through said cylinder, an upwardly-opening valve about said pump rod at the lower end of said cylinder through which valve water is adapted to enter said cylinder, means for reciprocating said cylinder, a plunger in said cylinder connected with said tubular pump rod, means for closing the upper end of said cylinder about said tubular pump rod, an upwardly-opening valve through said plunger, said tubular pump rod being provided with a port opening into the cylinder above the plunger, and an upwardly-opening valve in said pump rod below the said port.

8. In a pump, the combination of two aligned cylinders, means connecting said two cylinders together and providing ports into the adjacent ends of said cylinders, means for reciprocating said cylinders in unison, a tubular pump rod extending through the

upper cylinder down into the lower cylinder, an upwardly-opening valve adapted to close the lower end of the upper cylinder about said tubular pump rod, a plunger in each of said cylinders connected to said tubular pump rod, and an upwardly-opening valve in each of said plungers.

9. In a pump, the combination of two aligned cylinders, means connecting said two cylinders together and providing ports into the adjacent ends of said cylinders, means for reciprocating said cylinders in unison, a tubular pump rod extending through the upper cylinder down into the lower cylinder, an upwardly-opening valve adapted to close the lower end of the upper cylinder about said tubular pump rod, a plunger in the upper cylinder about said tubular pump rod and connected thereto, a plunger in the lower cylinder connected to the lower end of said tubular pump rod, and an upwardly-opening valve in each of said plungers.

10. In a pump, the combination of two aligned cylinders, means connecting said two cylinders together and providing ports into the adjacent ends of said cylinders, means for reciprocating said cylinders in unison, a tubular pump rod extending through the upper cylinder down into the lower cylinder, an upwardly-opening valve adapted to close the lower end of the upper cylinder about said tubular pump rod, a plunger in the upper cylinder about said tubular pump rod connected to the said pump rod, an upwardly-opening valve in said plunger adapted to close the upper end of the cylinder from the lower end thereof, a plunger in the lower cylinder connected to the lower end of said tubular pump rod, and an upwardly-opening valve through which water is adapted to pass upward from the lower end of the lower cylinder through said tubular pump rod.

11. In a pump, the combination of two aligned cylinders, means connecting said two cylinders together and providing ports into the adjacent ends of said cylinders, means for reciprocating said cylinders in unison, a tubular pump rod extending through the upper cylinder down into the lower cylinder, an upwardly-opening valve adapted to close the lower end of the upper cylinder about said tubular pump rod, a plunger in each of said cylinders connected to said tubular pump rod, an upwardly-opening valve in each of said plungers, and an upwardly-opening valve in the lower end of said lower cylinder.

12. In a pump, the combination of two aligned cylinders, means connecting said two cylinders together and providing ports into the adjacent ends of said cylinders, means for reciprocating said cylinders in unison, a tubular pump rod extending through the upper cylinder down into the lower cylinder,

an upwardly-opening valve adapted to close the lower end of the upper cylinder about said tubular pump rod, a plunger in each of said cylinders connected to said tubular pump rod, an upwardly-opening valve through the upper one of said plungers, an upwardly-opening valve in the lower plunger through which water is adapted to pass upward into said tubular pump rod, and an upwardly-opening valve in the lower end of said lower cylinder.

13. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, and means serving in coöperation with said first-named valve to prevent water from escaping from said tubular pump rod through said opening into said cylinder.

14. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, and means for closing the upper end of said cylinder about said tubular pump rod above said opening.

15. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, and means serving to force the water in the cylinder above said plunger through the said opening in said tubular pump rod.

16. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump

rod, and other means for forcing a supply of water upward through said tubular pump rod, said first-named valve serving to prevent water from escaping from said tubular pump rod through said opening into said cylinder.

17. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, a second cylinder in which said plunger operates, an upwardly-opening valve in the lower end of said second cylinder, an upwardly-opening valve in the lower end of said pump rod through which the water in the second cylinder below the plunger therein is adapted to pass upward through the pump rod, and means serving in coöperation with said first-named valve to prevent such water from escaping through the opening from said pump rod into said first-named cylinder.
18. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, and means coöoperating with said second plunger for forcing a supply of water upward through the said pump rod past said opening, the water being adapted to escape from said cylinder only through said opening into said pump rod.

19. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, an upwardly-opening valve in the lower end of said pump rod, and means coöoperating with said second plunger for forcing a supply of water upward through said last-named valve, said first-named valve serving to prevent such water from escaping through the opening from said pump rod into said cylinder.
20. In a pump, the combination of a cylinder, a tubular pump rod extending down through said cylinder, an upwardly-opening

valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, a second cylinder in which said plunger operates, an upwardly-opening valve in the lower end of said second cylinder, an upwardly-opening valve in the lower end of said pump rod through which the water in the second cylinder below the plunger therein is adapted to pass upward through the pump rod, and means serving in coöperation with said first-named valve to prevent such water from escaping through the opening from said pump rod into said first-named cylinder.

21. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, other means for forcing a supply of water upward through said tubular pump rod, and means for closing the upper end of said cylinder about said tubular pump rod above said opening.

22. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, means coöoperating with said second plunger for forcing a supply of water upward through the said pump rod past said opening, and means for closing the upper end of said cylinder about said tubular pump rod above said opening.

23. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plun-

ger into said tubular pump rod, a second plunger mounted on the lower end of said tubular pump rod, a second cylinder in which said plunger operates, an upwardly-opening valve in the lower end of said second cylinder, an upwardly-opening valve in the lower end of said pump rod through which the water in the second cylinder below the plunger therein is adapted to pass upward through the pump rod, and means for closing the upper end of said first-named cylinder about said tubular pump rod above the opening from said pump rod into said first-named cylinder.

24. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, means for reciprocating said cylinder and said tubular pump rod simultaneously in opposite directions, and means serving in coöperation with said first-named valve for preventing water from escaping from said tubular pump rod through said opening into said cylinder.

25. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second plunger mounted on the lower end of said tubular pump rod, means for reciprocating said cylinder and said tubular pump rod simultaneously in opposite directions, and means coöperating with said second plunger for forcing a supply of water upward through the said pump rod past the opening from said pump rod into said cylinder, said first-named valve serving to prevent such water from escaping through said opening into said cylinder.

26. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second cylinder connected with said first-named

cylinder, a second plunger mounted on the lower end of said tubular pump rod and adapted to work in said second cylinder, an upwardly-opening valve in the lower end of said second cylinder, an upwardly-opening valve in the lower end of said pump rod through which the water in the second cylinder below the plunger therein is adapted to pass upward through the pump rod, means for reciprocating said pump rod and said cylinders simultaneously in opposite directions, and means serving in coöperation with said first-named valve for preventing water from escaping through the opening from said pump rod into said first-named cylinder.

27. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, means for closing the upper end of said cylinder about said tubular pump rod above said opening, and means for reciprocating said cylinder and said pump rod simultaneously in opposite directions.

28. In a pump, the combination of a cylinder, a tubular pump rod extending down through said cylinder, an upwardly-opening valve about said tubular pump rod at the lower end of said cylinder through which water is adapted to pass upward into said cylinder, a plunger in said cylinder connected with said tubular pump rod, an upwardly-opening valve through said plunger, an opening from said cylinder above the plunger into said tubular pump rod, a second cylinder connected with said first-named cylinder, a second plunger mounted on the lower end of said tubular pump rod and adapted to work in said second cylinder, an upwardly-opening valve in the lower end of said second cylinder, an upwardly-opening valve in the lower end of said pump rod through which the water in the second cylinder below the plunger therein is adapted to pass upward through the pump rod, means for reciprocating said pump rod and said cylinders simultaneously in opposite directions, and means for closing the upper end of said first-named cylinder about said tubular pump rod above the opening from said pump rod into said first-named cylinder.

29. In a pump, the combination of a cylinder open at its lower end, an upwardly-opening valve adapted to close the upper end of said cylinder, a plunger in said cylinder, an upwardly-opening valve in said plunger, and means for reciprocating said

plunger and said cylinder simultaneously in opposite directions.

30. In a pump, the combination of a cylinder open at its lower end, a pump rod 5 extending down into said cylinder, an upwardly-opening valve adapted to close the upper end of said cylinder about said pump rod, a plunger in said cylinder connected with said pump rod, and means for reciprocating said pump rod and said cylinder simultaneously in opposite directions.

31. In a pump, the combination of two cylinders, a tubular pump rod communicating with both of said cylinders, plungers in 15 said cylinders respectively connected with said tubular pump rod, and means for reciprocating said pump rod whereby upon a stroke of the pump rod in one direction the water is forced upward out of one cylinder 20 through said pump rod and upon a stroke in the opposite direction the water is forced upward out of the other cylinder through said pump rod.

32. In a pump, the combination of two 25 cylinders connected together and movable in unison with each other, a tubular pump rod communicating with both of said cylinders, plungers in said cylinders respectively connected with said tubular pump rod and 30 movable therewith, and means for reciprocating said cylinders and said plungers simultaneously in opposite directions whereby upon a stroke of the plungers in one direction the water is forced upward out of 35 one cylinder through the said pump rod and upon a stroke of the said plungers in the opposite direction the water is forced upward out of the other cylinder through the said pump rod.

40. 33. In a pump, the combination of two aligned cylinders, a tubular pump rod extending through the upper cylinder and down into the lower cylinder, means for reciprocating said pump rod, means actuated by the 45 reciprocation of said pump rod for forcing the water from said lower cylinder upward through said pump rod, an opening between said pump rod and the upper cylinder, and means for preventing the escape of water 50 from the upper cylinder except through the opening from the cylinder into the pump rod.

34. In a pump, the combination of three 55 aligned cylinders, three plungers in said cylinders respectively, an upwardly-opening valve in each of the upper two plungers, and means for reciprocating said plungers in unison, each of the upper two plungers being adapted to force the water out of the cylinder in which it is located upon the upward stroke of the plungers and the lowermost plunger being adapted to force the water out of the lower cylinder upon the downward stroke of the plungers.

60. 35. In a pump, the combination of three

aligned cylinders, three plungers in said cylinders respectively, an upwardly-opening valve in each of the upper two plungers, and means for reciprocating said plungers and said cylinders simultaneously in opposite 70 directions, each of the upper two plungers being adapted upon the upward stroke of the plungers to force the water upward out of the cylinder in which such plunger is located and the lowermost plunger being 75 adapted upon the downward stroke of the plungers to force the water upward out of the lower cylinder.

36. In a pump, the combination of three aligned cylinders, three plungers in said cylinders respectively, an upwardly-opening valve in each of the upper two plungers, an upwardly-opening valve in the upper end of the uppermost cylinder, and means for reciprocating said plungers in unison, each 80 of the upper two plungers being adapted upon the upward stroke of the plungers to force the water upward out of the cylinder in which such plunger is located into position above the uppermost cylinder and the 85 lowermost plunger being adapted upon the downward stroke of the plungers to force the water upward out of the lower cylinder into position above the uppermost cylinder.

37. In a pump, the combination of three 90 aligned cylinders, three plungers in said cylinders respectively, an upwardly-opening valve in each of the upper two plungers, an upwardly-opening valve in the upper end of the uppermost cylinder, and means for 95 reciprocating said plungers and said cylinders simultaneously in opposite directions, each of the upper two plungers being adapted upon the upward stroke of the plungers to force the water upward out of 100 the cylinder in which such plunger is located into position above the descending uppermost cylinder and the lowermost plunger being adapted upon the downward stroke of the plungers to force the water 105 upward out of the lower cylinder into position above the rising uppermost cylinder.

38. In a pump, the combination of three aligned cylinders, three plungers in said cylinders respectively, a tubular pump rod 110 connected with said plungers and communicating with each of the lower two cylinders, an upwardly-opening valve in each of the upper two plungers, an upwardly-opening valve in the upper end of the uppermost cylinder, and means for reciprocating said tubular pump rod, the lower two plungers being adapted to act alternately to force the water out of the corresponding cylinders 115 upward through said tubular pump rod into position above the uppermost cylinder and the uppermost plunger being adapted to force the water out of the uppermost cylinder into position above said cylinder upon 120 the upward stroke of the said plunger.

39. In a pump, the combination of three aligned cylinders, three plungers in said cylinders respectively, a tubular pump rod connected with said plungers and communicating with each of the lower two cylinders, an upwardly-opening valve in each of the upper two plungers, an upwardly-opening valve in the upper end of the uppermost cylinder, and means for reciprocating said cylinders and said pump rod simultaneously in opposite directions, the lower two plungers being adapted to act alternately to force the water out of the corresponding cylinders upward through said tubular pump rod into position above the uppermost cylinder and the uppermost plunger being adapted to force the water out of the uppermost cylinder into position above said cylinder upon the downward stroke of the 20 said cylinder.

40. In a pump, the combination of three cylinders, three plungers in said cylinders respectively, means for reciprocating said three cylinders in unison, means for reciprocating said three plungers in unison in the opposite direction, means adapted upon the downward stroke of said cylinders to deliver the water from two of said cylinders into position above the descending uppermost cylinders, and means adapted upon the upward stroke of said cylinders to deliver the water from the remaining cylinder into

position above the ascending uppermost cylinder.

41. In a pump, the combination of three cylinders, three plungers in said cylinders respectively, means for reciprocating said three cylinders in unison, means for reciprocating said three plungers in unison in the opposite direction, means adapted upon the downward stroke of said cylinders to deliver the water from the upper two cylinders into position above the descending upper cylinders, and means adapted upon the upward stroke of said cylinders to deliver the water from the lower cylinder into position above the ascending uppermost cylinder. 45

42. In a pump, the combination of a well tube, three cylinders in said well tube in alignment with each other, three plungers in said cylinders respectively, means for reciprocating said three cylinders in unison, means for reciprocating said three plungers in unison in the opposite direction, means adapted upon the downward stroke of said cylinders to deliver the water from two of said cylinders to said well tube above said descending uppermost cylinder, and means adapted upon the upward stroke of said cylinders to deliver the water from the other of said cylinders to said well tube above said ascending uppermost cylinder. 50 55 60
